(57) **CLAIM**

The ornamental design for a bracelet, as shown and described.

DESCRIPTION

FIG. 1 is a front orthographic view of a first embodiment of a bracelet in a closed position.

FIG. 2 is a rear orthographic view thereof in a closed position.

FIG. 3 is a top orthographic view thereof in a closed position.

FIG. 4 is a right side orthographic view thereof in a closed position, the left side view being a mirror image of the right side view.

FIG. 5 is front orthographic view thereof in an open position;

FIG. 6 is rear orthographic view thereof in an open position;

FIG. 7 is a top orthographic view thereof in an open position.

FIG. 8 is a right side orthographic view thereof in an open position with the clasp in an open position.

FIG. 9 is a left side orthographic view thereof in an open position.

FIG. 10 is a rear perspective view thereof in a closed position.

FIG. 11 is a front perspective view thereof in a closed position; and,

FIG. 12 is a front perspective view thereof; in a closed position; the number sign and numerals not being part of the claimed design.

The structures shown in phantom or broken lines in FIGS. 1-12 form no part of the claimed design and are included only to illustrate an environment.
